Barber, Santa Monica, Calif.

Application November 18, 1929
Serial No. 408,086

19 Claims. (Cl. 20—20)

Our invention relates to improvements in doors, and particularly to folding doors, suitable for hangars, garages, warehouses and the like, where opening and closing of the usual type of door is rendered very difficult by reason of the necessary size and weight of the door.

A particular feature of our invention is the manner in which the door is mounted and folded for opening and closing movements, rendering such doors applicable to use in building constructions wherein head room is insufficient to accommodate vertically sliding doors or side room is insufficient to accommodate laterally sliding doors.

Further features of our invention reside in the mechanism we employ for opening and closing the door, and the manner in which the door is automatically folded and unfolded during opening and closing movements. The ease with which our improved type of door may be opened and closed permits heavier and more durable construction, particularly in doors of large size.

The merits of our invention, as well as the several novel features thereof, will be more fully set forth in the following specification, reference being made therein to the accompanying drawings wherein we have illustrated our preferred specific embodiment. In the drawings—

Fig. 1 is a side elevation of our door in closed position;

Fig. 2 is a view similar to Fig. 1, showing the door during its first opening movement or final closing movement;

Fig. 3 is likewise a side elevation of the door, showing it in full open position;

Fig. 4 is an enlarged, fragmentary, detailed view of the upper end of the door, in the position illustrated in Fig. 1;

Fig. 5 is a view similar to Fig. 4, showing the upper end of the door, in the position illustrated in Fig. 2;

Fig. 6 is an enlarged, fragmentary, detailed sectional view of the bottom of the door, illustrating a guide means as it is when the door is in the position illustrated in Fig. 1, the section being taken along the line 6—6 of Fig. 8;

Fig. 7 is a view similar to Fig. 6, taken in side elevation, illustrating the guide means as it is when the door is in the position illustrated in Fig. 2;

Fig. 8 is a fragmentary face view of the guide means shown in Figs. 6 and 7, being taken as indicated by the arrow 8 in Fig. 6;

Fig. 9 is an enlarged view, similar to Figs.

4 and 5, showing the door when it is in the position illustrated in Fig. 3;

Fig. 10 is a fragmentary face view of one side of the door, illustrating the operating mechanism, the view being taken when the door is in the position illustrated in Figs. 1 and 4;

Fig. 11 illustrates a modified form of operating means; and

Figs. 12, 13 and 14 are views diagrammatically illustrating modified arrangements of the principles we employ.

It is to be understood, in connection with the instant disclosure, that we herein show and describe only the preferred specific embodiment of the principles of our invention, primarily for the purpose of teaching to those skilled in the art the manner of constructing and using the same, and not for the purpose of limiting its use, and that we reserve the right to make such changes and modifications in structure and arrangement as will properly come within the scope of the claims appended hereto.

Referring now to the drawings, and first to Figs. 1, 2 and 3, the numeral 10 designates generally a wall having a door opening 11 therein, to be closed by the door, the door and opening being of such size that the door sections swing through the opening during opening and closing movements.

The door may be formed of a plurality of sections, hingedly joined together to fold one upon the other. In the present case we have shown our preferred embodiment to be composed of two door sections 12 and 13 hingedly joined together at 14. While the door sections may be mounted to move in a horizontal plane, through a door opening, during opening and closing movements, the main section being mounted to turn about a vertical axis, we have here shown, in our preferred specific embodiment, the door sections mounted to swing in a vertical plane during opening and closing movements. In this arrangement the door section 12—which we will hereinafter term the main section—the section 13 being termed hereinafter the auxiliary section—is mounted upon horizontally disposed spindles 15 at each side thereof to turn about a horizontal axis. Spindles 15 are supported in brackets 16 secured to the wall 10 at any convenient place adjacent the top and side of the door opening 11. Brackets 17, secured to the top edge 18 of the door section 12, provide pivotal bearing connections between the door section and spindles. Spindles 15 are positioned and connection made with the main door section

85

95
100
105
110

to permit movement of the door section 12 from the position illustrated in Fig. 1, through that illustrated in Fig. 2, to that shown in Fig. 3.

The relative sizes of the main section 12 and 5 the auxiliary section 13 may be arranged as desired, to suit particular conditions, but preferably, when only two are used, each will close substantially one-half of the opening 11.

Rails 19 extend upwardly above the top edge 10 18 of the door section 12, at either side thereof, and secured to their upper ends are counter-weights 20; these weights being formed of a plurality of plates 21, secured together and to the rails 19 by suitable bolts 22, so that their weights 15 may be varied as desired.

A chain or cable 23 is secured at one end to a fixed support, as at 24, passed around a roller 25, carried by a bracket 26 secured to the upper end of one of the rails 19, thence around a roller 20 27 carried by a bracket 28, preferably secured to the wall 10, thence over a roller 29, carried by a bracket 30, likewise preferably secured to the wall 10 immediately above the top of the door opening 11, thence downwardly and is connected 25 adjacent the lower edge of the auxiliary panel 13, as clearly illustrated in Fig. 2. The manner of connecting the chain or cable 23 with the auxiliary panel 13 is best illustrated in Fig. 8.

As precise relative positioning of the anchor 30 24, rollers 25, 27 and 29, as well as the point of connection with the auxiliary panel 13, cannot always be accomplished, and in order to maintain proper tension upon the cable 23, the form of connection with the auxiliary section 13 is, to an 35 extent, compensating. This is accomplished by providing a sleeve 31 pivotally connected at its lower end to a bracket 32, the latter being secured adjacent the lower edge of the auxiliary panel. A rod 33, secured at one end to the cable 40 23, extends through a cap 34 on the upper end of sleeve 31 and is provided on its inner end with a head 35. An expansile, helical spring 36, confined between head 35 and the cap 34, exerts the proper tension upon the cable 23 and 45 affords some compensation for slight variations in the required length of cable during movement of the door sections. The positioning of the anchor 24, rollers 25, 27 and 29, and the point of connection of the cable 23 with the auxiliary section 13, will, of course, be left to the skill of the mechanic in putting our invention to use.

The mechanism we prefer to employ for effecting movement of the main section 12, is best 55 illustrated in Fig. 10. An operating shaft 37 is revolvably journalled in suitable bearing blocks 38 secured at suitable points to the wall 10. This shaft may be rotated either manually or by motor. For manual rotation a sprocket 39 is keyed upon shaft 37 and is operatively connected with a similar sprocket 40 through the medium of a sprocket chain 41. Sprocket 40 is loosely mounted upon a jack shaft 42, the latter being suitably journalled in bearing blocks 43 supported upon wall brackets 44. A sheave 45 is 60 likewise loosely mounted upon shaft 42, and has a clutch member 46 adapted to releasably engage a complementary clutch member 47 on sprocket 40. Sheave 45 is axially slidably upon shaft 42, and its clutch member 46 is normally held in engagement with the complementary clutch member 47, through the medium of a bell crank 48 and contractile spring 49, the latter being connected between arm 50 and shaft 42. A pull 65 downward upon the cord 51 will effect disengagement of the complementary clutch members 70 75

46 and 47, and upon releasing it re-engagement will be effected through the medium of the spring 49. A chain or cable 52 passed around the sheave 45 provides a means for manually rotating the latter.

Shaft 37 may be mechanically rotated through the medium of a suitable, reversible, electric motor 53, mounted adjacent to it and operatively connected thereto through the medium of spur gears 54 and 55. When a motor 53 is employed for operative purposes the clutch members 46 and 47 will, of course, be disengaged as hereinbefore described.

The operative connection between the operating shaft 37 and the door section 12 is as follows: A yoke 56 is rotatably mounted upon shaft 37 through the medium of loose bearings 57. A screw 59 is revolvably journalled in a bearing 60, on yoke 56, being suitably held against axial movement therein, and is provided on one end 90 with a bevel gear 61 meshing with gear 58. The outer end of screw 59 screw-threadedly engages in a block 62, pivotally mounted upon a stub shaft 63 carried by a bracket 64, the latter being secured to the rail 19.

All of the operating mechanism heretofore described, including the cable 23, with its rollers 25, 27 and 29, and the form of connection with the auxiliary panel 13, may be at one side of the door, or it may all be duplicated on the 105 opposite side, shaft 37, for this purpose, extending along the wall to the opposite side of the door. Preferably the entire operating means will be provided at each side of the door.

In Figs. 6, 7 and 8 we have illustrated a means 110 for not only guiding the bottom edge of the auxiliary panel 13 to proper position upon closing of the door, but also to throw the auxiliary panel 13 off center during early opening movement of the door, so as not to place undue tension or strain upon the cable 23, which may not be compensated for by the form of connection with the lower panel 13. This means maintains the lower edge of the auxiliary section 13 somewhat in vertical alignment with the wall 10, 115 while its hinged connection 14 is moving laterally from the position shown in Fig. 1 to that shown in Fig. 2. This consists of a guide bar 65, longitudinally movable through a recess 66 in the lower edge of the auxiliary section 13. 120 A guide sleeve 67, through which the bar 65 slides, is pivotally mounted adjacent the lower end of the recess 66, upon a suitable bracket 68. The lower end of the bar 65 is preferably provided with a non-friction roller 69, adapted to 125 engage in a floor box or recess 70, preferably of the configuration shown in Fig. 6. The upper end of the bar 65 is provided with a pair of non-friction rollers 71, adapted to ride in an elongated guideway 72. Bar 65 is normally held in 130 extended position by the action of a contractile, helical spring 73, secured at its lower end to a fixed bracket 74 and at its upper end to the upper end of the bar 65, as shown.

In operation the door sections swing through a vertical plane, during opening and closing movements, from the position shown in Fig. 1 to that shown in Fig. 3, and vice versa, and during such movement the door sections foldably and unfoldably move relative to each other. Assuming the door to be closed, as shown in Fig. 1, opening movement is effected through manual rotation of the shaft 45, through the medium of chain or cable 52, which effects rotation of shaft 37, through the medium of

sprockets 40 and 39 and sprocket chain 41. Rotation of shaft 37 in the proper direction effects rotation of screw 59, through the medium of bevel gears 58 and 61, causing movement of block 62 along the screw, from the position shown in Figs. 1 and 4 to the position shown in Figs. 3 and 9, resulting in swinging the door section 12 upon its spindles 15, from a vertical to a horizontal position, relative to the door opening 11. Rotation of the shaft 37 in the opposite direction will cause block 62 to travel along the screw 59 from the position shown in Figs. 3 and 9 back to the position shown in Figs. 1 and 4, effecting closing movement of the door section 12, from a horizontal to a vertical position, relative to the door opening.

During opening and closing movements the auxiliary door 13 would normally depend in a vertical plane, but, due to the action of cable 23, it is folded upon the door section 12, as illustrated in Figs. 3 and 9. The positioning of the cable anchor 24, rollers 25, 27 and 29, and the point of connection of the cable 23 with the auxiliary section 13, is such that during opening and closing movements of the door the auxiliary panel 13 will be moved from the position shown in Fig. 1 to that shown in Fig. 3 and the cable 23 kept taut. As the door section 12 swings from vertical alignment, thus moving the hinged connection 14 and the upper edge of auxiliary section 13 laterally, the lower end of bar 65 is retained within the floor box 70 by the action of spring 73, as shown in Figs. 6 and 7. This keeps the lower edge of auxiliary section 13 practically in vertical alignment with the wall, throwing the upper edge of section 13 off center so as not to place undue strain upon cable 23. The length of bar 65 may be varied to suit particular conditions. While in open position, as shown in Fig. 3, spring 73 holds bar 65 in extended position, and as the section 13 swings downwardly, during closing movement, the lower end of bar 65 will engage in the floor box 70, thus bringing the auxiliary section 13 into proper closed position.

Counterweights 20 may be dispensed with if desired, but their retention adds to ease of operation, due to their balancing effect.

When the mechanism is operated by the motor 53, the operation is the same, suitable reversing gear being provided to effect opening and closing movements.

In Fig. 11 we have illustrated a modified form of means for operatively connecting shaft 37 with rail 19. This consists of an arm 75, fixed upon shaft 37, and having an angular upper end 76 engaging in an elongated slot 77 in the edge of rail 19.

How the invention may embody a door construction of more than two sections is diagrammatically illustrated in Fig. 12. Here sections 12 and 13, interconnecting chain or cable 23, and all the other elements except the added door section 13a, have the same functions as corresponding parts of Fig. 3. The only essential difference between the construction shown in the two figures is that sections 12 and 13 are relatively less extensive in Fig. 12, the difference being accounted for by the third section 13a which is merely hinged to the lower edge of section 13 to depend vertically therefrom at all stages of the door's operation.

Figs. 13 and 14 diagrammatically illustrate an improvement over the construction shown in Fig. 12 whereby the third and lowermost sec-

tion, in this case 13b, is caused to fold with the other sections when the door is open. The improvement consists in extending rails 78 upward from sections 13b above its hinged connection with section 13, and in providing cam-surfaces 79 on rails 19 to coact with rails 78 to force door section 13b into the folded position shown in Fig. 14. Preferably rails 78 have terminal non-friction rollers 80 to facilitate such action. In the operation of the door, the chain or cable 23, sections 12 and 13, and rails 19 serve in the same manner as in the preferred embodiment. Towards the end of the opening movement of the door, however, rollers 80 engage cam-surfaces 79 and fold section 13b against section 13, as shown in Fig. 14.

Having described our invention, we claim:

1. A door comprising: a plurality of door sections hingedly connected together to fold one upon the other; spindles upon which one of said sections is pivotally mounted to turn about a horizontal axis; means to cause said pivotally mounted section to turn upon said spindles and flexible means operated by said pivotally mounted section to cause folding and unfolding movement of one of said sections relative to the other.

2. A door comprising: a plurality of door sections hingedly connected together to fold one upon the other; spindles upon which one of said sections is pivotally mounted; means to cause said pivotally mounted section to turn upon said spindles; and flexible means operated by said pivotally mounted section to cause folding and unfolding movement of one of said sections relative to the other.

3. A door comprising: a plurality of door sections hingedly connected together to fold one upon the other; spindles upon which one of said sections is pivotally mounted; means to cause said pivotally mounted section to turn upon said spindles; and a flexible member secured at one end to a fixed support and connecting said door sections, whereby folding movement of said door sections, relative to each other, is effected upon movement of the pivotally mounted section.

4. A door comprising: a pair of door sections hingedly connected together to fold one upon the other; spindles upon which one of said sections is pivotally mounted to turn about a horizontal axis; guide means on the other of said sections; means to cause said pivotally mounted section to turn upon said spindles; and flexible means associated with said pivotally mounted section whereby folding and unfolding movement of said sections, relative to each other, is effected upon movement of the pivotally mounted section.

5. A door comprising: a plurality of door sections hingedly connected together to fold one upon the other; spindles upon which one of said sections is pivotally mounted; an operating shaft; an operative connection between said operating shaft and the pivotally mounted section, whereby the pivotally mounted section is caused to turn upon said spindles; and flexible means connecting said door sections to cause folding movement of said sections, relative to each other, upon movement of the pivotally mounted section.

6. A door comprising: a plurality of door sections hingedly connected together to fold one upon the other; spindles upon which one of said sections is pivotally mounted; an operating

- shaft; an operative connection between said operating shaft and the pivotally mounted section, whereby the pivotally mounted section is caused to turn upon said spindles; and a flexible member secured at one end to a fixed support and connecting said door sections, whereby folding movement of said door sections, relative to each other, is effected upon movement of the pivotally mounted section.
- 10 7. A door comprising: a pair of door sections hingedly connected together to fold one upon the other; spindles upon which one of said sections is pivotally mounted to turn about a horizontal axis; guide means on the other of said sections; means to cause said pivotally mounted section to turn upon said spindles; and flexible means connecting said door sections to cause folding movement of said sections, relative to each other, upon movement of the pivotally mounted section.
- 15 8. A door comprising: a pair of door sections hingedly connected together to fold one upon the other; spindles upon which one of said sections is pivotally mounted to turn about a horizontal axis; guide means on the other of said sections; means to cause said pivotally mounted section to turn upon said spindles; and a flexible member secured at one end to a fixed support and connecting said door sections, whereby folding movement of said door sections, relative to each other, is effected upon movement of the pivotally mounted section.
- 20 9. The combination with a wall having an opening therein, of a plurality of door sections hingedly connected together to fold one upon the other; spindles, fixed relative to said opening, upon which one of said sections is pivotally mounted to swing through the opening; means to cause said pivotally mounted section to turn upon said spindles; and a flexible member secured at one end adjacent the opening and connecting said door sections, whereby folding movement of said door sections, relative to each other, is effected upon movement of the pivotally mounted section.
- 25 10. The combination with a wall having an opening therein, of a plurality of door sections hingedly connected together to fold one upon the other; spindles, fixed relative to said opening, upon which the uppermost section is pivotally mounted to swing through the opening, about a horizontal axis; means to cause said pivotally mounted section to turn upon said spindles; and flexible means connecting said door sections to cause said sections to fold relative to the uppermost section upon movement of the uppermost section upon said spindles.
- 30 11. The combination with a wall having an opening therein, of a plurality of door sections hingedly connected together to fold one upon the other; spindles, fixed relative to said opening, upon which the uppermost section is pivotally mounted to swing through the opening, about a horizontal axis; guide means on the lowermost section; means to cause said pivotally mounted section to turn upon said spindles; and flexible means connecting said door sections to cause said sections to fold relative to the uppermost section upon movement of the uppermost section upon said spindles.
- 35 12. The combination with a wall having an opening therein, of a pair of door sections hingedly connected together to fold one upon the other; spindles, fixed relative to said opening, upon which the uppermost section is pivotally mounted to swing through the opening, about a horizontal axis; an operating shaft; an operative connection between said operating shaft and the pivotally mounted section, whereby the pivotally mounted section is caused to turn upon said spindles; and flexible means connecting said door sections to cause folding movement of said sections relative to each other, upon movement of the pivotally mounted section.
- 40 13. The combination with a wall having an opening therein, of a pair of door sections hingedly connected together to fold one upon the other; spindles, fixed relative to said opening, upon which the uppermost section is pivotally mounted to swing through the opening, about a horizontal axis; guide means upon the other of said sections; means to cause said pivotally mounted section to turn upon said spindles; and flexible means connecting said door sections to cause said sections to fold, relative to each other, upon movement of the uppermost section upon said spindles.
- 45 14. The combination with a wall having an opening therein, of a plurality of door sections hingedly connected together to fold one upon the other; spindles, fixed relative to said opening, upon which the uppermost section is pivotally mounted to swing through the opening, about a horizontal axis; means to cause said pivotally mounted section to turn upon said spindles; and a flexible member secured at one end adjacent the opening and connecting said door sections, whereby folding movement of said door sections, relative to each other, is effected upon movement of the pivotally mounted section.
- 50 15. The combination with a wall having an opening therein, of a pair of door sections hingedly connected together to fold one upon the other; spindles, fixed relative to said opening, upon which the uppermost section is pivotally mounted to swing through the opening, about a horizontal axis; means to cause said pivotally mounted section to turn upon said spindles; and a flexible member secured at one end adjacent the opening and connecting said door sections, whereby folding movement of said door sections, relative to each other, is effected upon movement of the pivotally mounted section.
- 55 16. The combination with a wall having an opening therein, of a pair of door sections hingedly connected together to fold one upon the other; spindles fixed relative to the top of said opening upon which the uppermost section is pivotally mounted to swing through the opening about a horizontal axis; an operating shaft; an operative connection between said operating shaft and the pivotally mounted section, whereby the pivotally mounted section is caused to turn upon said spindles; and flexible means connecting said door sections to cause folding movement of said sections relative to each other, upon movement of the pivotally mounted section.
- 60 17. The combination with a wall having an opening therein, of a pair of door sections hingedly connected together to fold one upon the other; spindles fixed relative to the top of said opening upon which the uppermost section is pivotally mounted to swing through the opening about a horizontal axis; an operating shaft; an operative connection between said operating shaft and the pivotally mounted section, whereby the pivotally mounted section is caused to turn upon said spindles; and a flexible mem-

ber secured at one end to a fixed support and connecting said door sections, whereby folding movement of said door sections, relative to each other, is effected upon movement of the 5 pivotally mounted section.

18. The combination with a wall having an opening therein, of a pair of door sections hinged together to fold one upon the other; spindles, fixed relative to the top of said 10 opening, upon which the uppermost section is pivotally mounted to swing through the opening about a horizontal axis; an operating shaft; an operative connection between said operating shaft and the pivotally mounted section, where- 15 by the pivotally mounted section is caused to turn upon said spindles; guide means on the other of said sections; and a flexible member secured at one end to a fixed support and connecting said door sections, whereby folding

20

movement of said door sections, relative to each other, is effected upon movement of the pivotally mounted section.

19. The combination with a wall having an opening therein, of a pair of door sections hinged together to fold one upon the other; spindles fixed relative to the top of said opening upon which the uppermost section is pivotally mounted to swing through the opening about a horizontal axis; an operating shaft; an operative screw connection between said operating shaft and the pivotally mounted section, whereby the pivotally mounted section is caused to turn upon said spindles; and means driven by the uppermost section to fold the lowermost section against said uppermost section.
